UNITED STATES PATENT OFFICE.

ANDREW J. KOLASHINSKE, OF GLENWOOD CITY, WISCONSIN.

GATE-HINGE.

1,130,908.

Specification of Letters Patent.

Patented Mar. 9, 1915.

Application filed August 21, 1914. Serial No. 857,915.

To all whom it may concern:

Be it known that I, ANDREW J. KOLASHINSKE, a citizen of the United States, residing at Glenwood City, in the county of St. Croix and State of Wisconsin, have invented certain new and useful Improvements in Gate-Hinges; and I do hereby declare the following to be a full, clear, and exact description of the invention, such as will enable others skilled in the art to which it appertains to make and use the same.

This invention relates to a gate hinge and the primary object of the invention is the provision of a novel form of hanger for a gate, by means of which the gate structure is pivotally supported by a post.

Another object of this invention is the provision of a gate hanger as specified which has a plurality of anti-friction rollers mounted within sleeves and about a vertical rod, to which sleeves the gate structure is connected for swinging, so as to provide a free and easy moving gate.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which:—

Figure 1 is a view in elevation of a fragment of a gate showing the improved hanger attached thereto. Fig. 2 is a view in elevation of a fragment of a gate showing the opposite side of a hanger to that which is exposed

in Fig. 1 of the drawings. Fig. 3 is a vertical section through a part of a hanger taken on the line 3—3 of Fig. 2. Fig. 4 is a cross sectional view on the line 4—4 of Fig. 1. Fig. 5 is a section on the line 5—5 of Fig. 2.

Fig. 6 is a section on the line 6—6 of Fig. 2, and Fig. 7 is a top plan view of one of the gate attaching hinges.

Referring more particularly to the drawings, 1 designates the supporting vertical gate post of a fence, which has a metallic strap 2 secured to the upper end thereof and positioned transversely therefrom. A vertical bar or rod 3 is secured to the horizontal strap 2 and extends parallel with the post 1. The rod 3 has its lower end seated in a bearing 4 formed in a block 5, which block

is inserted in the ground adjacent the base of the post 1. The rod 3 has a sleeve 6 positioned about the upper end of the same, which sleeve rests upon an annular collar 7 formed integrally with the bar 3 or secured against the longitudinal movement upon the bar in any suitable manner. The sleeve 6 has tangential lugs 9 and 10 formed thereupon which lugs have a plate 11 secured thereto by means of bolts 12. The bolts 12 extend along opposite sides of the end piece 14 of the gate structure and have their outer ends inserted through a plate 15 which abuts the opposite side of the end post 13 of the gate 14 from the plate 11, for swingably and securely connecting the gate structure 14 to the rod 3 and the gate post 1 as is clearly shown in Figs. 1 and 4 of the drawings.

The sleeve 6 has a plurality of anti-friction rollers 16 positioned vertically therein and encompassing the outer surface of the rod 3. The sleeve 6 is held against upward vertical movement by a removable collar 17 which is held in place upon the rod 3 by a set screw 18.

The lower end of the rod 3 has a sleeve 20 mounted thereupon, which sleeve has its upper end enlarged as at 21 being provided with an increased bore for spacing the inner sides of the enlarged end 21 from the rod 3 so as to permit of the insertion of anti-friction rollers 32 therein, and about the outer surface of the rod 3 so as to decrease the friction generated by the movement of the sleeve 20 upon the rod 3. The sleeve 20 is held against vertical movement upon the rod 3 by a collar 23, which has an upwardly extending flange. The collar 23 is held in place upon the rod 3 by a set screw 24.

The sleeve 20 has a transversely projecting extension 25 formed upon the lower end thereof, which projection has annularly disposed sides 26 and 27, that engage the side 100 of the base board 28 of the gate structure 14 as is clearly shown in Fig. 5 of the drawings. The projection 25 has a vertically extending web 29 formed thereupon which has a horizontally disposed platform 30 formed upon its upper end. The end piece 13 of the gate structure is recessed as at 31 so as to receive the horizontal plate or platform 30 therein, for supporting the weight of the gate to prevent the rear hinged side 110 of the same from sagging. The gate structure 14 has a diagonally extending rod con-

nected thereto, to prevent sagging of the gate and to facilitate the maintenance of the proper shape of the gate structure.

From the foregoing description taken in

connection with the accompanying drawings the advantages of the construction and of the method of operation of the improved gate will be readily apparent to those skilled in the art to which this invention appertains and, while in the foregoing description the principle of the operation of this invention has been described together with various features of construction, it is to be understood that certain minor features of construction, combination and arrangement of parts may be altered to suit practical conditions provided such alterations are comprehended within the scope of what is claimed.

20 What is claimed is:—

1. In a gate structure, the combination of a vertical gate post, a gate, a rod positioned parallel with said gate post and rigidly connected thereto, the lower end of said rod being rectangular and seated in a block mounted in the ground below said gate for preventing rotation of said rod, a plurality of sleeves rotatably mounted upon said rod, said sleeves being rigidly connected to said gate for swingably supporting said gate by

said rod, and anti-friction rollers mounted within said sleeves and encompassing said rod to facilitate the swinging movement of said gate.

2. In a gate structure, the combination with a vertical gate post and a gate, of a rod positioned adjacent the gate post and parallel therewith, said rod having its upper end rigidly connected to said gate post, the lower end of said rod being rectangular and seated in a bearing block which is inserted in the ground for preventing rotation of said rod, a plurality of sleeves rotatably mounted upon said rod, one of said sleeves having tangential lugs formed thereupon, said lugs being securely attached to said gate, transversely extending flanges formed upon another of said sleeves for securely attaching said last named sleeve to said gate, whereby said gate will be swingably supported by said vertical rod, and anti-friction rollers positioned within said sleeves and about said rod for facilitating the swinging movement of said gate.

In testimony whereof I affix my signature in presence of two witnesses.

ANDREW J. KOLASHINSKE.
